United States Patent

Des. 238,846
Patented Feb. 17, 1976

238,846

NUT DISPENSER

William Finnegan, 7200 Beverly Blvd.
Los Angeles, Calif. 90036

Filed Mar. 6, 1974, Ser. No. 448,554

Term of patent 14 years

Int. Cl. D7—06

U.S. Cl. D7—98

FIG. 1 is a plan view of a nut dispenser showing my new design.

FIG. 2 is a front elevational view thereof.

FIG. 3 is a side elevational view as seen from the right side of FIG. 2, the side opposite being a mirror image thereof; and

FIG. 4 is a rear elevational view thereof.

The bottom is substantially plain.

I claim:

The ornamental design for a nut dispenser, as shown and described.
